AUTOMATIC INTERMITTENT FLUSH VALVE

William S. White, Denver, Colo.

Application May 28, 1934, Serial No. 727,936

3 Claims. (Cl. 137—93)

My invention relates to improvements in a flush valve of the type generally employed in connection with urinals.

It is a common practice to provide a valve of this type for flushing urinals. The urinal fixture, in most instances, is an earthenware composition having a glazed surface which contains numerous, minute interstices. If used when this glazed surface is dry, the urine penetrates the interstices of the fixture, and if permitted to remain therein, causes a disagreeable odor, as well as staining the fixture. The flushing action is intended to cleanse the fixture and avoid the aforementioned obnoxious conditions, but many users neglect to operate the valve and the fixture often remains in a dry condition for considerable periods of time, during which it is frequently used.

It is an object of my invention to provide a flush valve which opens periodically to flush a fixture with which it is connected, with a measured volume of water, the opening and closing movements of the valve being entirely automatic.

Another object of the invention is the provision of a valve particularly adapted for maintaining the surface of a fixture in a moist condition by impounding a restricted, continuous flow of water during predetermined intervals necessary to collect a volume of water sufficient for a flushing action, and utilizing the pressure of the restricted flow in effecting an automatic operation of the valve to flush the fixture, when the required volume is available.

It is a further object of the invention to provide an automatically operating valve of the character described, which also contains a manually-operable control to produce a flushing action.

Other objects reside in details of construction and in the combination and arrangement of parts, as will fully appear in the course of the following description.

Referring now to the drawings, in the several views of which like parts have been similarly designated,

Figure 1 represents a sectional elevation of a preferred embodiment of the valve assembly embodying the features of the present invention;

Figure 2 represents a sectional elevation of another embodiment of a valve assembly embodying the features of the invention;

Figure 3 a section taken along the line 3—3, Figure 1, and

Figure 4 a section taken along the line 4—4, Figure 2.

Referring now to the drawings, the valve casing 6 is provided with an inlet 7, an outlet 8, and with an annular valve seat 9 on its interior surface. A valve 10 cooperates with the seat 9 to control the flow of water between the inlet and the outlet, and provides an end wall of a control chamber 12 within the casing 6. The valve is provided with an annular recess in which a resilient washer 59 is fitted, to form a fluid-tight closure when the valve 10 is held on seat 9. 10

A piston element 13 reciprocates in the control chamber 12 and a coil spring 14 bearing against a wall of the control chamber 12 engages the piston 13. A cap 15, fitted in the casing 6, has a vent 16 to eliminate compression exteriorly of 15 control chamber 12.

In the embodiment illustrated in Figures 1 and 3, the inlet 7 enters into a chamber 17 in a hollow cylindrical housing 18, supported integrally in spaced relation to the cylindrical interior of 20 the casing 6 by spokes 19. The space 20 between the housing and the casing provides a passage from the control chamber to the outlet. A restricted opening 21 in the chamber permits communication with the outlet 8, and a tilt valve 22, 25 seated on an annular gasket 23 in the chamber 17 and having a stem 24 extending thru the opening 21, controls the flow of water therethru. A coil spring 25 in the chamber bears upon the tilt valve for normally holding the same on its seat. 30

A port 26 leading from the chamber 17 is narrowed at 27 to provide a seat for a ball valve 28, the seat being notched at 29 to provide a bleed opening. The port 26 terminates in a passage 30 which communicates with control chamber 12. 35

The piston element 13, in the embodiment illustrated in Figures 1 and 3, comprises a two-part casing comprising a flanged section 31 and a flanged section 32, fastened in flange-to-flange 40 relationship with a cup washer 33 held between the flange 34 of the section 31 and the flange 35 of the section 32. The flanges 34 and 35, together with the washer 33, form a shoulder on the piston exposed to the pressure of water entering 45 the control chamber 12 thru the passage 30, which provides a fluid-tight closure that defines the control chamber 12.

The section 31 is widened at 36 to provide an abutment for the spring 14. A stem 37 slidably 50 fitted in an aperture 38 of the section 32 extends into the section 31 and terminates in a flanged head 39, which provides an abutment for a coil spring 40 on the head. At its opposite end, the spring 40 bears upon the section 32. 55

For manual operation of the valve, a handle 41 fulcrumed in an end of a housing 42, screwed upon an end of the casing 6, actuates a pushrod 43 slidably supported in an aperture 44 in the housing 42. A coil spring 45 between and bearing upon a head 46 and an abutment 47 carried on the pushrod within the housing 42, effects a return of the pushrod to its normal position after the valve-actuating movement. The pushrod 43 terminates adjacent the stem 24, and when the handle 41 is rocked, the pushrod bears against the stem and unseats tilt valve 22.

In the operation of the embodiment of the valve illustrated in Figures 1 and 3, water entering thru inlet 7 from a water main or other source (not shown) and maintained under a substantially uniform pressure, fills the chamber 17 closed by tilt valve 22, the pressure of the water forcing ball 28 against its seat 27. As the chamber 17 fills, the pressure of the water forces a small flow thru the bleed opening 29 and thru the passage 30 into control chamber 12. The increasing pressure of the water on the cup washer 33 moves the piston away from valve 10, against the resistance of spring 14. At the same time the pressure of the water holds valve 10 on its seat 9. Due to the large superficial area of the valve 10 with relation to the circumferential extent of the control chamber, a comparatively slight pressure is sufficient to hold the valve on its seat, whereas a considerably greater pressure would be required if the valve had a relatively small superficial area.

The movement of the piston 13 causes a compression of the spring 40, until the piston 13 has traveled a predetermined distance from valve 10, when the compression of the spring 40 will develop sufficient force to overcome the pressure of the water on valve 10, whereupon the valve is moved off its seat 9 and the water flows out of control chamber 12 thru passage 20 and into outlet 8, to spray a fixture (not shown) connected with the outlet.

As soon as the water flows past valve 10, the spring 14 urges the piston against valve 10 and reseats the valve, whereupon refilling of the control chamber 12 progresses in the manner indicated. It is to be understood that the amount of water flowing thru the bleed opening 29 is relatively small so that a considerable time interval is provided between the flushing operations while chamber 12 is being filled. These intervals are not so extended, however, that the fixture becomes dry between the flushing actions.

The arrangement of the springs 14 and 40 is calculated to restrain the opening movement of the valve 10, until a supply of water is maintained in the control chamber 12 of just sufficient volume to adequately flush the fixture with which the valve is connected, thereby eliminating the possibility of any waste of water.

When it is desired to manually actuate the valve, the handle 41 is rocked to unseat tilt valve 22. Water from the inlet 7 is permitted to flow directly to the outlet 8 while the tilt valve 22 is unseated, and in addition, water in the control chamber flows thru passage 30 and unseats ball 28 due to the decrease of pressure in chamber 17.

The consequent release of pressure in the control chamber 12 unseats valve 10, and water flows from the control chamber 12 thru passage 20 to the outlet, until the chamber is emptied. As soon as the manual movement of the handle 41 is terminated, the pushrod 43 is returned to its normal position by spring 45. Spring 25 thereupon

reseats tilt valve 22, and refilling of control chamber 12 resumes in the above-described manner.

The embodiment of the valve illustrated in Figures 2 and 4 incorporates the above-described principles of operation, and involves only slight structural differences. The casing 6 is provided with an enlargement 48 in which a port 49 is provided for communication between the inlet 7 and the control chamber 12. The port 49 adjacent the inlet 7 terminates in a seat 50 for a ball valve 51. The seat is notched at 52 to provide a bleed opening.

The piston 13, consisting of a cup washer 33, held between plates 53 and 54 to form a shoulder exposed to the pressure of water entering control chamber 12, carries a stem 55, and the valve 10 is apertured at 56 to permit sliding movement of the stem 55 therein. A flanged head 57 on the stem provides an abutment for a spring 40 on the stem, which has its opposite end bearing upon the valve 10. A casing 58, fastened on the valve 10 and holding the washer 59 in the recess in the valve, encloses the spring 40 and stem 55, and extends into the outlet passage 8 of the casing.

A handle 41 is fulcrumed on the enlargement 48 and actuates a pushrod 43, slidably supported in an aperture 60 in the enlargement 48. The pushrod has an end adjacent the ball 51, and its opposite end is provided with a head 46 in a recess 61 in the enlargement. A spring 45 is held on the pushrod within the recess 61, with one end engaging the head and its opposite end engaging a surface of the enlargement.

The casing 6 is recessed at 62 above the control chamber 12, and the interior of the casing is connected with the recess by a port 63. The junction of the port and recess provides a seat 64 for a ball 65. A by-pass 66 leading from the recess 62 establishes communication between the recess 40 and the outlet passage 8.

The operation of the embodiment of the valve illustrated in Figures 2 and 4 is similar to the operation heretofore described. The pressure of water is inlet 7 seats ball 51, and a restricted flow 45 is forced thru bleed opening 52 into control chamber 12. The valve 10 is normally seated in a manner already explained, and the pressure of water in the control chamber raises piston 13 while holding valve 10 on its seat. When the 50 contraction of spring 40 develops a force sufficient to overcome the pressure of water exerted against valve 10 to hold same on its seat 9, the opening movement of the valve 10 is effected, and water in the control chamber 12 flows past seat 9 into the 55 outlet passage 8. The release of pressure in the control chamber permits the spring 14 to reseat valve 10 thru the intermediary of valve 13 and stem 55, and refilling of the control chamber is resumed.

When manual operation is desired, rocking of handle 41 unseats ball 51, permitting a rapid flow of water from the inlet 7 into control chamber 12. The piston quickly raised a distance sufficient to contract the spring to a point where 65 opening movement of valve 10 is effected to thereby release a flow of water from control chamber 12 into outlet passage 8. When pressure on the handle 41 is removed, the ball 51 reseats, and refilling of control chamber progresses in the man- 70 heretofore described.

If washer 33 leaks and water escapes into the hollow interior of the casing 6, the compression caused by upward movement of the piston 13 unseats ball 65, closing vent 16, and the water 75

flows out thru port 63 and passage 66 into outlet passage 8. During this action, closing of vent 16 by ball 65 prevents any splashing of water therethru.

5 It is to be understood that changes and modifications may be resorted to within the scope of the invention as defined in the claims.

What I claim and desire to secure by Letters Patent is:

10 1. A flush valve comprising a casing having an inlet, an outlet and a valve seat, a valve cooperating with the seat to control the flow of water between the inlet and the outlet, a spring-pressed piston reciprocating in the casing and defining a 15 control chamber at a side thereof, the piston being normally in contact with the valve whereby the piston spring also serves to press the valve onto its seat there being a passageway between the inlet and the chamber, the casing having a 20 by-pass between its interior beyond the control chamber and the outlet for the removal of water leaking past the piston, the piston being movable against the resistance of its spring by the pressure of water in the chamber, a spring positioned between the piston and the valve, functioning when compressed, to produce a force tending to open the valve and means for compressing the valve spring by movement of the piston, to unseat the 25 valve and move it to fully open position by subsequent expansion of its spring, when the piston is moved by the water entering the control chamber, whereby to effect a flow of water from the chamber to the outlet.

30 2. A flush valve comprising a casing having an inlet, an outlet and a valve seat, a valve cooperating with the seat to control the flow of water

between the inlet and the outlet, a spring-pressed piston reciprocating in the casing and defining, with the valve, a control chamber at a side thereof, there being a passage between the inlet and the chamber, a check valve located in the passage 5 for restricting the flow from the inlet into the chamber to regulate the rate of flow of water into the control chamber, the piston being movable away from the valve and against the resistance of its spring by the pressure of water in the chamber, and toward and into contact with the valve by the action of its spring, and means comprising a spring for opening the main valve by movement of the piston against the action of its spring, whereby to effect a flow of water from the chamber to the outlet. 10

3. A flush valve comprising a casing having an inlet and an outlet, a valve and a piston cooperatively connected for reciprocating movement within the casing and defining between them a 20 control chamber, there being a passage in the casing for establishing communication between the inlet and the control chamber, a check valve in the passage, there being a second passage between the control chamber and the outlet, a tilt 25 valve normally closing said second passage, a spring pressing upon the piston, the piston being movable against the resistance of its spring by the pressure of water in the control chamber, and a second spring disposed between the piston and 30 the valve, to be compressed by the movement of the piston and acting upon the valve to effect by its expansion an opening movement thereof, when its pressure overbalances the fluid pressure in the chamber. 35

WILLIAM S. WHITE.
